CLOTHESPIN OR LIKE ARTICLE

Henry J. Peterson, Webster City, Iowa

Application May 29, 1936, Serial No. 82,465

6 Claims. (Cl. 24—261)

The principal object of my invention is to provide a clasp for holding clothes and like on a line that is of non-rust all metal construction, thereby making for durability in use, lightness in weight, and economy in manufacture.

A further object of this invention is to provide an all metal clothespin that is constructed from a single length of spring square or round rod wire.

10 A still further object of my invention is to provide a spring metal clothespin that successfully grips and holds the clothes on the line against accidental detachment, and has only one spring bow or loop portion.

15 A still further object of my invention is to provide a spring metal clothespin that does not mar or mark the clothes being held.

A still further object of this invention is to provide a metal clothespin that has a low center 20 of gravity when in use and one that has no tendency to twist or become distorted.

25 Still further objects of my device is to provide an all metal clothespin that is sanitary, compact, easily cleaned, substantially unbreakable and can not be put on the clothes in a wrong position.

30 Still further objects of my invention is to provide a nonporous clothespin or fastener that is easily and quickly put on the clothes and as easily 30 and quickly removed therefrom.

35 A still further object of my invention is to provide a clothespin or like that is free from slivers, and of exceptional clothes holding characteristics.

35 These and other objects will be apparent to those skilled in the art.

40 My invention consists in the construction, arrangement, and combination of the various parts of the device, whereby the objects contemplated 40 are attained as hereinafter more fully set forth, pointed out in my claims and illustrated in the accompanying drawing, in which:

Fig. 1 is a front view of my clothespin in use.

Fig. 2 is a side view of my clothespin not in use.

45 Fig. 3 is a front view of my clothespin not in use and more fully illustrates its construction.

Fig. 4 is a back view of my clothespin in use.

The clothespins now in general use are mainly 50 of two types, i. e., the all wooden ones having a slit for straddling the clothes to be held, and the wooden jaw ones having a closing metal spring. These clothespins are objectionable in that they are porous and unsanitary, hard to clean or keep clean, have splinters and projections that tend to catch and damage the clothes,

do not successfully hold the clothes, are top heavy, cumbersome, are not easily operated, and have a tendency to split and/or break.

Referring to the drawing I have used the numeral 10 to designate the ordinary clothesline or 5 like. The numeral 11 designates a cloth or other flexible sheeting folded over the line 10. My clothespin is formed from a single length of spring rod wire as shown in the drawing and may be considered to consist of a spring bow loop 10 portion 12, a finger portion 13 and a U-portion 14.

The loop portion 12 is substantially a vertical ring or circle when viewed from the side as shown in Fig. 2, but when viewed from the front or back one can observe that its two bottom ends 15 are spaced apart as shown in Fig. 3. The finger portion 13 is continuation of the inner lower end of the loop ring and extends in a general downward direction therefrom. The U-portion 14 is a continuation of the other lower end of 20 the loop ring 12 and extends generally, first downwardly in spaced relationship to the finger 13, then horizontally past the longitudinal plane of the finger 13, then upwardly in spaced relationship to and on the other side of the finger 13, 25 and then inwardly and horizontal to slidably engage the loop ring as shown in Fig. 3. The finger 13 is bowed outwardly or "humped" at its upper end, then has its center portion bowed inwardly, and then has its lower free end bent slightly 30 outwardly and downwardly.

I have used the numeral 15 to designate this outwardly bowed portion of the finger 13. In each of the upper end portions of the two side lengths of the U-portion 14 is also an outwardly 35 bowed or "hump" portion which I have designated by the numerals 16 and 17. These two bowed portions 16 and 17 are located at each side of the bowed portion 15 and each extends in the opposite direction from the direction of 40 the bowed portion 15, as shown in the drawing. Obviously, when the device is in use the bowed portion 15 of the finger 13 will extend around one side of the clothes engaging the line 10 and the bowed portions 16 and 17 will extend around 45 the other side. The lower end portion of the U-portion is bent downwardly and outwardly as the lower end portion of the finger, but in the opposite direction from that of the lower portion of the finger. This construction facilitates the 50 placement of my device on the clothes on the line by guiding the same between the holding finger and holding U-portion. Also there is no danger of the lower end of the finger gouging the cloth to be held.

To put my device on, it is usually grasped by the loop portion 12 and merely manually forced downwardly as far as it will go, as shown in Fig. 1. The complementary "hump" portions 15 and 16—17 will snap into place around the line 10 over which the clothes have been folded, thereby securely holding the clothes to and on the line, and eliminating any tendency of the clothespin to remove itself from its holding position. Obviously the spring loop 15 will yieldingly hold the finger portion and U-portion toward each other. By having the free upper end of the U-portion bent inwardly to enter and engage the loop portion, any undesirable twisting of the device when in use is eliminated. One reason for this is that both sides of the U-portion are substantially of equal strength and both depending on the loop portion for support and resilient spring action. When the finger portion and U-portion are forced away from each other, the free end of the U-portion will slidably ride back on the inner side of the loop portion, thereby eliminating torque while at the same time receiving cooperative support and action from the loop portion. From this it will be seen that the finger portion and U-portion are successfully yieldingly held toward each other by a single loop portion 12. By the line 10 closely approaching the loop portion the device will not be too heavy.

To remove my clothespin from use it is merely necessary to manually pull it upwardly and away from contact with the clothes being held. As it is all metal there will be no wood splinters or like to catch on the clothes or perforations to catch and hold dirt. Dampness will not swell or harm my clothespin as there is no wood or like present. Obviously my clothespins may be easily washed and cleaned and immediately dried as they do not absorb liquid. As the bowed portions 15, 16 and 17 are aligned with each other, the device will be properly held in alignment on and to the line 10.

Some changes may be made in the construction and arrangement of my improved clothespin or like without departing from the real spirit and purpose of my invention, and it is my intention to cover by my claims any modified forms of structure or use of mechanical equivalents which may be reasonably included within their scope.

I claim:

1. In a clothespin constructed of a single strand of spring material, a circular upper loop portion bent in the central portion of said strand, a downwardly extending finger portion extending from one end of said loop portion, a U-shaped portion having one of its ends extending downwardly from the other end of said loop portion, having its two side lengths resting in spaced relationship at each side of said finger portion, and its free end bent inwardly to slidably engage solely the inner side of the end portion of said loop portion that extends into said finger portion.

2. In a clothespin constructed of a single strand of spring material, a circular upper loop portion bent in the central portion of said strand, a downwardly extending finger portion extending from one end of said loop portion and having an outwardly bowed section, a U-shaped portion having one of its ends extending downwardly from the other end of said loop portion, having its two side lengths resting in spaced relationship at each side of said finger portion, a bowed sec-

tion in each of its side lengths, and its free end bent inwardly to slidably engage solely the inner side of the end portion of said loop portion that extends into said finger portion.

3. In a clothespin constructed of a single strand of spring material, a circular upper loop portion bent in the central portion of said strand, a downwardly extending finger portion extending from one end of said loop portion, a downwardly and outwardly formed section on the free end of said finger portion, a U-shaped portion having one of its ends extending downwardly from the other end of said loop portion, having its two side lengths resting in spaced relationship at each side of said finger portion, a downwardly and outwardly bowed section on the lower end portions of each of its two side lengths, and its free end bent inwardly to slidably engage solely the inner side of the end portion of said loop portion that extends into said finger portion.

4. In a clothespin constructed of a single strand of spring material, a circular upper loop portion bent in the central portion of said strand, a downwardly extending finger portion extending from one end of said loop portion and having an outwardly bowed section, a U-shaped portion having one of its ends extending downwardly from the other end of said loop portion, having its two side lengths resting in spaced relationship at each side of said finger portion, a bowed section in each of its side lengths, and its free end bent inwardly to slidably engage solely the inner side of the end portion of said loop portion that extends into said finger portion; said outwardly bowed section of said finger portion extending in an opposite direction from the bowed sections in each of the side lengths of said U-shaped portion.

5. In a clothespin constructed of a single strand of spring material, a circular upper loop portion bent in the central portion of said strand, a downwardly extending finger portion extending from one end of said loop portion and having an outwardly bowed section, a U-shaped portion having one of its ends extending downwardly from the other end of said loop portion, having its two side lengths resting in spaced relationship at each side of said finger portion, a bowed section in each of its side lengths, and its free end bent inwardly to slidably engage solely the inner side of the end portion of said loop portion that extends into said finger portion; said bowed section in each of the side lengths of said U-shaped portion being in alignment with each other and in alignment with the bowed section in said finger portion.

6. In a clothespin constructed of a single strand of spring material, a circular upper loop portion bent in the central portion of said strand, a downwardly extending finger portion extending from one end of said loop portion and having an outwardly bowed section, a U-shaped portion having one of its ends extending downwardly from the other end of said loop portion, having its two side lengths resting in spaced relationship at each side of said finger portion, a bowed section in each of its side lengths, and its free end portion of said loop portion that extends into said finger portion; said bowed sections in the side lengths of said U-shaped member and the bowed section in said finger portion being in close proximity to said loop portion.

HENRY J. PETERSON.
